US0D1011190S

(12) **United States Design Patent** (10) **Patent No.:** **US D1,011,190 S**
(45) **Date of Patent:** **** Jan. 16, 2024**

(54) **SCALLOPED WAVE POST**

(71) Applicant: **Rational Packaging LLC**, Springfield, TN (US)

(72) Inventor: **Shawn M. Parella**, Greenbrier, TN (US)

(73) Assignee: **Rational Packaging LLC**, Springfield, TN (US)

(**) Term: **15 Years**

(21) Appl. No.: **29/726,544**

(22) Filed: **Mar. 4, 2020**

Related U.S. Application Data

(63) Continuation-in-part of application No. 16/244,676, filed on Jan. 10, 2019, now Pat. No. 10,899,524, (Continued)

CLAIM

The ornamental design for a scalloped wave post, as shown and described.

DESCRIPTION

FIG. 1 is a lower, right perspective view of a scalloped wave post, showing my new design;

FIG. 2 is an upper, right perspective view thereof;

FIG. 3 is a bottom view thereof;

FIG. 4 is a top view thereof;

FIG. 5 is a right side view thereof;

FIG. 6 is a left side view thereof;

FIG. 7 is a front side view thereof; and,

FIG. 8 is a rear view thereof.

1 Claim, 7 Drawing Sheets
